(57) **CLAIM**

The ornamental design for an automobile body, as shown and described.

DESCRIPTION

FIG. 1 is a perspective view of the front, right, and top of an automobile body showing our new design;

FIG. 2 is a perspective view of the rear, right, and top thereof;

FIG. 3 is a front view thereof;

FIG. 4 is a rear view thereof;

FIG. 5 is a right side view thereof; and,

FIG. 6 is a top plan view thereof.

The elements shown in broken lines are for illustrative purposes only and form no part of the claimed design.

A left side view is omitted since the left side view is substantially symmetrical to the right side view shown in FIG. 5.
